Flint & Rogers,

Shoe Heel,

Nº 22,328.

Patented Dec. 14, 1858

Fig. 2.

Fig. 3.

UNITED STATES PATENT OFFICE.

SAM'L. FLINT AND ROBERT S. ROGERS, OF LYNN, MASSACHUSETTS, ASSIGNOR TO WM. F. JOHNSON, OF SAME PLACE.

HEEL FOR BOOTS AND SHOES.

Specification of Letters Patent No. 22,328, dated December 14, 1858.

To all whom it may concern:

Be it known that we, SAMUEL FLINT and ROBERT S. ROGERS, of Lynn, in the county of Essex and State of Massachusetts, have invented a new and Improved Manufacture of Heels for Boots or Shoes, and do hereby declare that the same is fully described and represented in the following specification and the accompanying drawings, of which—
10 Figure 1, denotes a side view; Fig. 2, a bottom view, and Fig. 3, a longitudinal and vertical section of a shoe having the said invention applied to it.

The nature of the invention consists in a combination of a wooden body or heel and an elastic or india rubber guard applied within the heel and so as to make a part thereof in manner as hereinafter described.

In such drawings, A, exhibits a shoe, of 20 which, a is the sole and B, the heel. This heel is constructed mainly of wood and has a cylindrical or a tapering cavity, b, bored upward through it or into it for the reception of a cylindrical or other proper shaped 25 block or piece of vulcanized india rubber c, arranged in it as shown in the drawings the said block of rubber being made to project a short distance beyond the outer bearing surface of the heel. In this way, the 30 india rubber forms a spring to relieve the heel from concussion and noise and it also operates to prevent to a considerable extent, the wooden part of the heel from being worn down. It also prevents the shoe from slipping on ice when said shoe may be worn in 35 winter. The whole forms a heel of great value and one which can be made much cheaper than a heel of the same size composed of layers of leather fastened together 40 either by the ordinary process of pegging or stitching.

We are aware that heels have been made

hollow or chambered, and with what is usually termed "hard india rubber" and that such heels have had elastic balls or meniscus 45 shaped pieces or plates of india rubber let into the same, and to work toward and away from the perforated plate of metal fixed in the heel. We are also aware that such elastic meniscus balls and perforated 50 metallic plates have been applied to the soles of shoes, the whole being described in Charles Goodyear's application for a patent rejected September 27th, 1856. Therefore, we do not claim such, our improved manu- 55 facture of heel, differing essentially there- from, as in the first place, the india rubber part is a solid block or cylinder, filling the whole space provided within the wooden body for its reception. Secondly, the heel 60 contains no unfilled space or chamber be- tween it and the ball, and in which the rub- ber may vibrate as it does in the heel de- scribed by the said Goodyear. Furthermore, 65 the body part of our heel is made of wood. Taking it as a whole it is a new and im- proved article of manufacture, wherein the rubber acts as a guard to the wooden body or as a preventive of wear of the same.

We do not claim a heel made wholly of 70 india rubber, nor one composed of metal and india rubber, but

What we do claim is—

An improved manufacture of heel made 75 of wood and india rubber combined and ar- ranged together substantially as set forth.

In testimony whereof we have hereunto set our signatures.

SAMUEL FLINT.
ROBERT S. ROGERS.
